UNITED STATES PATENT OFFICE.

MILON J. TRUMBLE, OF LOS ANGELES, CALIFORNIA.

CONTINUOUS REFLUXING STILL.

Application filed September 8, 1924. Serial No. 736,436.

My invention relates to the art of refining petroleum oils and more particularly to the art of cracking oils.

It is a well known fact that if a petroleum oil is subjected simultaneously to heat and pressure, a rearrangement of the molecules thereof takes place, a portion of the oil breaking up into low boiling point oils and into heavier reaction products.

10 It is an object of my invention to provide an apparatus by which the cracking of oil can be very expeditiously carried on.

Further objects and advantages of the invention will be made evident hereinafter.

15 Referring to the drawing which is entirely diagrammatic,

1 is any convenient type of cracking still which is mounted in a furnace 2 which is heated by an oil or gas burner 3. Other 20 types of still or furnace may be substituted therefor, without departing from the spirit of my invention.

Oil is delivered preferably continuously to the still 1 from an oil supply pipe 4 through a pressure pump 5. The still 1 is provided with a dome 6 having an outlet pipe 7 which connects with a refluxing coil 8 situated in a rerun chamber 9. The lower end of the coil 8 is connected through a pipe 10 with a perforated pipe 11 immersed in the oil in the still 1. Vapor is also taken from the still 1 through a pipe 15 having a pressure regulating valve 16 and into a conventional design of condenser 17. This con-

15 denser is preferably cooled by water admitted through a pipe 18 and taken off through a pipe 19. The condensates produced in the condenser 17 are delivered through a pipe 20 into the rerun chamber 9, any surplus oil

20 accumulating in this chamber being taken off through a pipe 25 and delivered to a pump 26, which in turn delivers the oil under pressure into the still 1. A petcock 30 is provided in the pipe 7. Vapor may be

25 taken from the top of the rerun chamber 9 through a pipe 35 which is connected to a condenser 36. The condensates produced in the condenser 36 are taken off through a pipe 37. Uncondensed vapors are taken from

30 the condenser 36 through a pipe 38 and from the condenser 17 through a pipe 39. Residuum may be withdrawn from the still through a pipe 40.

The method of operation is as follows:

35 The still 1 is being charged with oil by means of the pump 5 to about the level

shown, the still is heated to a cracking temperature by means of the burner 3. During the preliminary heating a rapid evaporation takes place from the still and vapors are delivered through the pipe 7 into the refluxing coil 8. This refluxing coil is immersed in condensate from the condenser 17 and the vapors therein are rapidly cooled, forming condensates which are passed down through the pipe 10 and through the perforations in the pipe 11 into the body of oil in the still 1. In starting, originally contained gas or air may be removed from the pipe 7 and the refluxing coil 8 through the petcock 30. 70 The vapors withdrawn from the still 1 through the pipe 15 are condensed in the condenser 17 and are delivered in the form of a cooled condensate into the rerun chamber 9 through the pipe 20. The liquid in the rerun chamber 9 is heated by the refluxing coil 8 and a distillation takes place therefrom. The temperature of the liquid in the rerun chamber is at all times sufficiently low to prevent the reevaporation therefrom of anything having a higher boiling point than the desired product. This desired product passes off as a vapor through the pipe 35, is condensed in the condenser 36 and delivered as a product through the 85 pipe 37. Any surplus liquid collecting in the rerun chamber 9 is a distillate of higher boiling point than the desired product and is delivered through the pipe 25 to the pump 26 and returned to the still 1 for retreatment. 90

It will be noted that the refluxing coil 8 with the pipes 7, 10 and 11 form a closed system without any outlet from the still. During the operation of the process there is a continuous flow of hot vapor into the refluxing coil and continuous condensation therein, the condensates being returned to the still 1 for refluxing. A pressure sufficient to insure good cracking operation is maintained on the still 1 by the pressure regulating valve 16, which is so constructed that it holds the pressure in the pipe 15 and in the still 1 at a predetermined pressure. The pumps 5 and 26 serve to force liquid back into the still under this pressure. 100 105

My invention involves the conception of applying to a cracking still a refluxing coil arranged for a continuous circulation, and condensation of the products which it is desired to reflux.

I claim as my invention:

1. An apparatus for cracking oils com-

- back from said refluxing coil to said perforated pipe; a condenser; means for delivering vapor from said still to said condenser; a pressure regulating valve, between said still and said condenser, set to maintain a superatmospheric pressure on said still; walls forming a rerun chamber in which said refluxing coil is situated; means for delivering condensates from said condenser 5 still to said refluxing coil; means for delivering condensates directly back from said refluxing coil to said still; a condenser; means for delivering vapors from said still to said condenser; a pressure regulating valve in said means for delivering vapors from said still to said condenser, said valve being set to maintain a pressure on said still and said refluxing coil; means for delivering condensates from said condenser to the space inside said vessel about said refluxing coil; means for withdrawing vapors from said vessel; and means for delivering liquid from said vessel to said still. 20
- 10 to said rerun chamber; a pump connected to take surplus liquid from said rerun chamber and force it under superatmospheric pressure into said still; and means for condensing vapors produced in said rerun chamber. 25
- 15 9. In an oil refining apparatus, the combination of: a still, means for feeding the oil to be treated into said still; a refluxing coil; a vessel surrounding said refluxing coil; means for delivering vapor from said

In testimony whereof, I have hereunto set my hand at Los Angeles, California, this 25 2nd day of Sept., 1924.

MILON J. TRUMBLE.
